Fig. 15

FIGURE 1 is a top plan view of an opener for flexible lids, showing my new design;

FIGURE 2 is a bottom plan view thereof;

FIGURE 3 is a side elevation thereof;

FIGURE 4 is an end elevation thereof;

FIGURE 5 is an end elevation from the opposite end;

FIGURE 6 is a perspective view thereof;

FIGURE 7 is a perspective view facing the opposite way;

FIGURE 8 is a perspective view from the other side;

FIGURE 9 is a perspective view facing the opposite way;

FIGURE 10 is a magnified section taken on the line 10-10 of FIGURE 1;

FIGURE 11 is a magnified section taken on the line 11-11 of FIGURE 2;

FIGURE 12 is a magnified section taken on the line 12-12 of FIGURE 1;

FIGURE 13 is a magnified section taken on the line 13-13 of FIGURE 5;

FIGURE 14 is a magnified section taken on the line 14-14 of FIGURE 1; and

FIGURE 15 is a magnified section taken on the line 15-15 of FIGURE 2.

I claim:

The ornamental design for an opener for flexible lids, as shown.
